UNITED STATES PATENT OFFICE.

ALEXANDER WITTENBERG, OF NEW YORK, N. Y., ASSIGNOR TO AUTOSALES CORPORATION, A CORPORATION OF NEW YORK.

COIN-CONTROLLED MACHINE.

Application filed June 8, 1918. Serial No. 238,825.

To all whom it may concern:

Be it known that I, ALEXANDER WITTENBERG, a citizen of the United States, and a resident of New York, in the county of New York and State of New York, have invented certain new and useful Improvements in Coin-Controlled Machines, of which the following is a specification.

My invention relates generally to coin-controlled machines and has for its object the provision of safety means whereby the coin-box into which the deposited coins drop is rendered inaccessible from the outside of the machine, even should certain parts of the outside casing be forcibly wrenched off by an unscrupulous person.

For this purpose I provide a locking mechanism for the coin-box to hold the latter in an inaccessible position and prevent movement of the same into an accessible position, even if a portion of the front wall of the casing be broken away. This locking mechanism is so arranged that it cannot be moved into position to release the coin-box unless a certain section of the front wall of the casing be removed.

In the preferred form of my invention, the front wall of the casing consists of three removable sections, which are so constructed and arranged that the uppermost section must first be removed before the intermediate section can be removed, and the intermediate section must be removed before the lower section can be removed. The locking mechanism for the coin-box cannot be moved into unlocking position until the intermediate section has been removed, and the unlocked coin-box cannot be moved into accessible position until the lowermost section of the front wall of the casing has been removed. Therefore, before access can be had to the coin-box, it is necessary that all three sections of the front wall of the casing be removed. This, of course, is only done by the authorized attendant in charge of the machine.

The objects and advantages of my machine will become apparent from the detailed descriptions of the accompanying drawings in which—

Fig. 1 shows a cross-section, partly broken away, of a machine embodying my invention;

Fig. 2 is a fragmentary view in plan taken

on line 2—2 of Fig. 1, showing the mounting of the locking bolt for the coin-box; and

Fig. 3 is a view in perspective of the adjustable locking bolt for the coin-box.

The outer casing of the machine comprises side walls 1 (of which only one is shown), a top 2, a bottom 3, and a front wall consisting of the removable sections 3, 4 and 5. The back of the casing is not shown in the drawings.

The section 3 is in reality the front panel of the machine which closes the upper section of the casing where the magazines are arranged. This panel, which usually carries a looking-glass or suitable advertising matter, is locked in place on the casing by any suitable means, which I have not deemed it necessary to illustrate, as the same will be well understood.

The part which I have called the section 4, is in the form of a top plate which is horizontally slidable between the sides of the casing. This top plate is locked in position on the casing by the front panel 3 when the latter is in normal position. This interlocking between the panel 3 and the top plate 4 may be carried out in any suitable way. In the drawing I have shown the plate 4 provided with an upwardly standing lug 6 at the rear, which abuts against the lower edge of the front panel 3, thereby locking the plate 4 against removal. The top plate 4 preferably slides in grooves (not shown) in the sides 1 of the casing.

The part 5, which I have called the lowermost section of the front wall of the casing, is a front plate of suitable construction which is locked against removal by the top plate 4. In the drawing, I have shown the front plate 5 provided at its lower end with a casting 7, which is formed with a discharge opening 8 through which the ejected goods reach the purchaser. The casting 7 is at its lower end formed with lugs 9 which extend into the bottom 3 of the casing. The top plate 4 is at its front preferably provided with a depending flange 10 which protects the joint between the top plate 4 and the front plate 5.

It will be clear from the foregoing, that before the top plate 4 can be slid forwardly, the panel 3 must be removed, and before the front plate 5 can be lifted out of engagement with the bottom 3 of the casing, the

top plate 4 must be removed. The interlocking of these three sections may, of course, be carried out in other ways than that shown.

In the chamber formed by the side walls 5 of the casing and the plates 4 and 5, is located suitable coin-controlled mechanism which I have indicated as a whole by M. As this mechanism forms no part of my invention, I have not deemed it necessary to 10 describe the same in detail. I will only say, that when a suitable coin is deposited through the coin-slot 11 in the top plate 4, the same is received in the coin-seat 12 of the mechanism, and when the coin-seat is 15 then pushed rearwardly by means of the plunger 13, the coin in the coin-seat 12 acts upon the pin 14 of the pivoted member 15 to cause ejection of the articles from the magazine. For further details of this ejecting 20 mechanism, reference may be had to Cook Patent No. 627,685, issued June 27, 1899. Any suitable form of coin-controlled mechanism may be used. The hand-plunger 13 extends through an opening 16 in the front 25 plate 5, and this opening is sufficiently large to allow the lugs or pins 9 to be lifted out of the bottom 3 of the casing without disturbing the mechanism M, which is rigidly mounted in the casing. If desired, the front 30 plate 5 may be locked to the rigid framework of the coin-controlled mechanism by means of one or more hooks 17, which are pivotally connected to the upper end of the front plate 5.

35 Below the coin-controlled mechanism M is mounted the coin-box indicated as a whole by C. In the drawings I have shown this coin-box slidably mounted between the side walls of the casing, grooves or channels 18 being provided for that purpose. As the 40 coins are discharged from the mechanism M after they have performed their intended function, they drop into the coin-box C from which the attendant then collects them at 45 certain intervals. As seen from Fig. 1, the coin-box C is normally in an inaccessible position, and it is normally locked in this position by a locking mechanism which in the present instance I have illustrated in the 50 form of a bolt B. This bolt is mounted in a suitable bracket, indicated as a whole by K, and held in fixed position in any suitable way. In the drawings I have shown the bracket K secured to a fixed cross-bar 19 by means of bolts or screws 20. The bracket 55 K is provided with upper and lower arms 21 and 22, which have aligned openings through which the bolt B extends. The lower end of the bolt B engages or rests 60 close to the lug 23 of the coin-box C, whereby the latter is locked against forward movement. The upper end 24 of the locking bolt B is shown in the form of a horizontal extension which rests in close proximity to the 65 top plate 4, whereby upward movement of

the bolt into releasing position is impossible as long as the plate 4 remains in normal position on the casing.

It will be clear from the foregoing, that in order to gain access to the contents of the 70 coin-box C, the attendant must first remove the front panel 3, then slide out the top plate 4, then lift out the front plate 5, and then lift the bolt B in releasing position, whereupon the coin-box may be slid 75 forwardly and its contents removed. If desired, the bolt B may be provided with a cross-pin 25 and a cross pin 26. The cross-pin 25 limits the upward movement of the bolt. The cross-pin 26 prevents movement 80 of the bolt into unlocking position unless the pin is first brought into alignment with the slot 27 in the arm 22 of the bracket K.

While I have herein shown and described a machine of particular construction, I would 85 have it understood that my invention is not limited to the details herein set forth, it being obvious that changes may be made without departing from the scope of the invention as defined in the appended claims. 90

Having thus described my invention what I claim as new and desire to secure by Letters Patent of the United States, is:

1. In a coin-controlled machine, a casing provided with a removable front panel 95 adapted to be locked in place, a horizontally slideable top plate adapted to be locked in place by said panel when the latter is in position on the casing, a vertically shiftable front plate extending below said top 100 plate and locked against vertical movement by said top plate when the latter is in position on the casing, a horizontally slideable coin-box below said top plate and back of said front plate, and a vertically movable 105 bolt arranged between said top plate and said coin-box for normally locking the latter against forward movement, said bolt being locked against movement into releasing position by said top plate when the latter is in 110 normal position.

2. In a coin-controlled machine, a casing provided with a removable front panel adapted to be locked in place, a top plate removably mounted on said casing and adapted to be locked in place by said panel when the latter is in position on the casing, a removable front plate extending below said top plate and adapted to be locked against removal by said top plate when the latter is in position on the casing, a movable coin-box mounted in said casing below said top plate and back of said front plate, coin-controlled mechanism arranged between said top plate and said coin-box, and a manually operable member movably supported above said coin box and adapted normally to engage said box and thereby lock the same against movement, said locking means being movable into unlocking

position only after removal of said top plate, whereby said coin-box is movable into accessible position only when said top plate and said front plate are removed.

5 3. In a coin-controlled machine, a casing provided with a removable front panel adapted to be locked in place, a horizontally slideable top plate adapted to be locked in place by said panel when the latter is in position on the casing, a removable front plate extending below said top plate and locked against removal by said top plate when the latter is in position on the cas-

ing, a horizontally slideable coin-box mounted below said top plate and back of said front plate, and manually operable means for locking said coin-box against forward movement, said locking means being movable into releasing position only after removal of said top plate, whereby said coin-box is movable into accessible position only when said top plate and said front plate are removed.

In witness whereof, I hereunto subscribe my name this 3rd day of June, 1918.

ALEXANDER WITTENBERG.
